CARAFE

Wayne M. Smythe, 11967 E. Rivera Road,
Santa Fe Springs, Calif. 90670

Filed Apr. 23, 1971, Ser. No. 137,113

Term of patent 14 years

Int. Cl. D9—01

U.S. Cl. D9—117

FIG. 1 is a perspective view of a carafe showing my new design;

FIG. 2 is a side elevational view thereof, all sides being identical;

FIG. 3 is a bottom plan view thereof; and

FIG. 4 is a top plan view thereof.

I claim:

The ornamental design for a carafe, as shown and described.
